UNITED STATES PATENT OFFICE.

HENRY KREJCA, OF PEARL RIVER, NEW YORK.

SUCTION FEEDING MACHINE.

Application filed June 18, 1923. Serial No. 646,196.

To all whom it may concern:

Be it known that I, HENRY KREJCA, a citizen of United States, residing at Pearl River, in the county of Rockland and State of New York, have invented certain new and useful Improvements in Suction Feeding Machines, of which the following is a specification.

This invention relates to improvements 10 in apparatus for feeding single sheets of paper from a stack or pile of the same, one after another, at any desired rate of speed, so long as may be required.

One of the several objects of the invention 15 is to provide an apparatus having a detachable platform provided with pivoted, caster-like wheels, by which it may be moved from place to place in the manner of a truck, receiving a load of paper from a stock supply and thereafter returned to the apparatus, engaged with vertical guiding columns and an elevating mechanism so that the uppermost sheets are brought level with the plane of dispensation and thereafter raised 25 in conformity with the discharge of each sheet.

Another purpose is to produce means for 30 loosening the upper sheets, permitting the entrance of air therebetween and tending to destroy any static electricity, otherwise, in combination to the vacuum between adjacent, closely compacted sheets, causing them to adhere tenaciously together and preventing their free, independent movement.

35 A further aim is in the provision of automatic sucker devices clamping upon the uppermost sheet, then raising and projecting the same forward to enter between feed rollers and thereupon releasing the sheet.

40 Other objects are, to provide means preventing the discharge of more than a single sheet at each delivery to the press or other device to which the paper is fed; to co-ordinate the several instrumentalities to 45 operate in time and harmony to produce an efficient operative structure in which manual labor is reduced to a minimum, supervision only being required.

These several aims and objects, together 50 with others which will become apparent as the description progresses, are accomplished by the novel design, construction and combination of parts hereafter described and

illustrated in the accompanying drawings, forming a part hereof, and in which:— 55

Figure 1 is a plan view of an embodiment of the invention.

Figure 2 is a rear elevational view thereof.

Figure 3 is a side elevational view of the same. 60

Figure 4 is a transverse sectional view taken on line 4—4 of Figure 1.

Figure 5 is a similar sectional view taken on line 5—5 of Figure 1.

Figure 6 is an elevational view looking 65 from the opposite side of the apparatus.

Figure 7 is a fragmentary sectional view taken approximately on line 7—7 of Figure 2.

Figure 8 is a sectional view illustrating 70 the construction of the sucker head.

Referring to the drawing more in detail, the numeral 15 designates a pair of side beams suited to rest upon the floor, these beams having between them at the front a 75 rigid cross beam 16 firmly securing them in spaced relation.

A pair of columns 17 extend upward at the front from the side beams, a similar pair 18 being disposed at the rear, both 80 pair supporting side frame elements 19 and 20 respectively at the right and left hand sides of the apparatus, the frame sides being stiffened by a cross beam 21 extending between the front columns. 85

An elongated rectangular frame is composed of end beams 23 and side beams 24 over which is removably engaged the platforms proper, the same being provided with upstanding guide rods 25 used to position 90 the paper.

Extending down at each corner of the frame are swivelled truck wheels or casters 26 permitting trundling the platform upon any level surface, as from a storage of paper 95 to the mechanism.

This platform is of such length as to fit between the rear uprights 18 and the end beams are provided with guide blocks 27 and 28 adapted to contact with the rear side 100 of the uprights, limiting the advance of the platform and slide as the platform is raised.

When the platform is then engaged by the uprights, it is held from being moved outwardly by pairs of pins 29 making sliding contact with the front surfaces of the 105

uprights, these pins being formed with loops 30 fixed in plates 31 adjacent the inner sides of the end beams 23 and are projected or retracted by rods 32 rotatable in

5 the beams 24 by their extending bent handles 33, said rods having crank throws 34 operable in the loops 30.

Each of the several end beams 23 contain recesses 35 open at the top and in 10 which may be inserted sheaves 36 rotatable upon pins 37 fixed in the plates 31 and movable with them upon operating the handles 33.

A shaft 40 is journalled in the frame 15 sides 19 and 20, this shaft having fixed upon it drums 41 adjacent the frames, one of the drums, next the side 20 being fast with a ratchet 42 engaged by a pawl 43 drawn into operative position by a spring 44.

20 Cables 59, fixed at one end, are wound upon the drums, the bights of the cables passing around the sheaves 36 so as to raise the platform when the shaft 40 is turned in one direction.

25 The end of the shaft 40 projecting through the frame 20 has fixed upon it a worm wheel 45, spaced from the frame by a plate 46, pivoted at 47, the plate having a slot in which the shaft operates as the 30 plate is moved.

Said plate is provided with bearings 48 in which is mounted a shaft 49 carrying a worm 50 engageable with the worm wheel 45 and provided with a reduced extension 25 having a hand wheel 51 by which the worm may be rotated.

The worm 50 is held in engagement with the wheel 45 by means of a pin 52 fixed in a spring arm 53 attached at its upper end 40 to the frame side and extending down to make contact with a projecting lug 54 carried on the platform element 23 so that as the platform is raised a certain height, the arm will be moved outwardly, allowing the plate 46 to turn on its pivot and disconnect the worm from the wheel 45, this effect being accomplished by gravity assisted by a pull spring 55.

The drive shaft 60, passing through the 50 front of the frame, has fixed at one end a spur gear 61 beyond which is a cam 62 having a single throw, this cam actuating a lever 63 the hub 64 of which encircles the shaft 49 and actuates it by means of a ratchet contained in the hub so that at each movement of the lever, by means of the cam, the shaft is given an intermittent progressive movement, which in turn is transmitted to the hoisting shaft 40, thus raising the platform in a gradual manner.

A feed shaft 65, parallel to the drive shaft is driven by it by means of a pinion 66, an intermediate pinion 67 meshing with the gear 62, as best seen in Figure 3.

65 Fixed on the shaft 60 at its opposite end

is a cam 68 operating against a roller 69 fixed on the end of an arm 70 containing a slot 71 through which the shaft 60 extends.

A spring 72 normally maintains the roller 70 against the cam 68 and pivoted to the arm is another arm 72' adjustably clamping a tube 73, fixed in eccentric bushings 74 rotatable in the side frames 19 and 20, and attached to the tube 73 is a flexible hose 75 75 leading to a suction device (not shown), whereby a partial vacuum is produced.

A pin 76 is engageable by a pivoted dog 77 operated by a link 78 attached to a lever 79 whenever it is desired to prevent the 80 tube 73 from turning.

Attached to the tube 73 are a pair of rigid levers 80, adjustably clamped thereon, these levers carrying sucker heads 81 of rubber and provided with spring controlled valves 82 to which are engaged flexible tubes 83 connecting with the tube, and a feeler disc 84 for actuating the valve is arranged axially of the suckers 81.

It is also to be noted that a port 85 is 90 formed in the frame communicating with an opening in the eccentric when in a certain position, whereby the vacuum in the tubes and suckers is broken to release the sheet of paper previously raised by them. 95

The advance edge of the paper blanks resting on the platform are guided and alined by a pair of vertical rods 86 secured in the cross bars of the frame and the upper sheets of the paper are loosened from 100 the pile by opposed toothed elements 87 driven by a gear train, generally indicated at 88 in Figure 4, from the driven shaft 60, these gear trains being carried in brackets 89 hanging pendant from the shaft 60 105 and guided at their lower ends by engagement with a transverse rod 90 disposed between the frame sides.

The rod 90 has fixed to it a pair of fingers 91, curved to contact with the top of 110 the pile and to clear the shaft 65. Motion is transmitted to the rod 90 by means of a crank arm 92 operated by a crank 93 fixed to the drive shaft 60.

Another cam 94 fixed to the shaft 60 115 operates a lever 95 fixed on a rod 96, said rod carrying arms 97 upon the ends of which are friction wheels 98, arranged with relation to rolls 99 on the high speed shaft 65.

120 A series of paper fingers 100 are secured to another rod 101 to which the lever 79 is fixed, these fingers delivering the sheets of paper outwardly from the machine.

In operation, the platform having been 125 loaded with a supply of paper sheets and engaged with the uprights 18, the sheaves and cables being in position, the first adjustment or rise of the platform is accomplished by using the hand wheel 51, bring 130

ing the top of the paper pile to the required height.

The worm is then in mesh with the wheel 45 and the platform will be raised by reason of the cam 62 and associated parts.

A constant suction is maintained in the pipe 75, communicated to the tube 73 and thence to the sucker heads, which are lowered to engage the uppermost sheet, raised 10 and advanced forward due to the cam 68, to bring the adhering sheet between the rolls 99 and wheels 98, causing them to grasp the sheet which is then liberated from the suckers due to the escape of air through 15 the port 85.

The rolls and friction wheels then advance the sheet upon the fingers 100, the next sheet being confined by the fingers 91, which, as has been seen are moved out of 20 the way upon the descent of the suckers for the next sheet.

It is to be noted that the sharp spurs of the elements 87 act to raise the edges of the sheets, allowing the entrance of air between, 25 coincidently with the raising effect of the suckers, assuring a positive feed of a single sheet only.

Although the foregoing is descriptive of

the preferred embodiment of the machine, it is intended to be illustrative rather than 30 restrictive and it is within the scope of the appended claims to make minor changes which do not embrace invention.

Having thus described my invention, what I claim as new and desire to secure by 35 Letters Patent, is:—

1. A paper feeding apparatus having a pair of uprights, drums at the ends of a horizontal shaft rotatable in the uprights, a platformed truck, means for detachably 40 engaging said truck to the uprights to slide thereon, sheaves rotatably engaged in said truck, and cables operated by said drums engaging said sheaves.

2. A paper feeding apparatus having a 45 pair of stationary uprights, a wheeled platform slideable thereon, means for intermittently raising the platform by power, means on said platform for automatically disconnecting the raising means, means for retaining the platform when in a raised position, and means for detaching the platform bodily from the apparatus.

In witness whereof I have affixed my signature.

HENRY KREJCA.
